COMBINATION PORCH LIGHT AND NUMBER PLATE

Filed Feb. 26, 1924

FIG. 1.

FIG. 2.

FIG. 3.

INVENTOR
W. DOUGLAS

BY *William H. Douglas*
ATTORNEYS.

UNITED STATES PATENT OFFICE.

WILLIAM DOUGLAS, OF TORONTO, ONTARIO, CANADA.

COMBINATION PORCH LIGHT AND NUMBER PLATE.

Application filed February 26, 1924. Serial No. 695,339.

To all whom it may concern:

Be it known that I, WILLIAM DOUGLAS, a subject of the King of Great Britain, and a resident of the city of Toronto, in the county 5 of York, in the Province of Ontario, Canada, have invented certain new and useful Improvements in Combination Porch Lights and Number Plates, of which the following is a specification.

10 My invention relates to improvements in combination porch lights and number plates, and the object of the invention is to devise a unitary structure which may readily be secured in position, and by which a number 15 may be always clearly visible at night time, and which may be readily adapted by an unskilled person to carry any number of figures evenly spaced and centred, as hereinafter more particularly explained.

20 Fig. 1 is a perspective view of my device supported upon a wall.

Fig. 2 is a vertical section through Fig. 1.

Fig. 3 is a detail view of my number plate.

25 In the drawings like characters of reference indicate corresponding parts in each figure.

1 indicates a wall provided with the usual mortar joints 2, between the bricks.

30 3 is a panel which is preferably formed of wood, and is secured to the wall by means of screws 4 and 5 extending into the mortar joints.

35 6 is a hood secured to the upper portion of the panel and preferably provided with glass panels 7 arranged round the same and within which is mounted an electric light fixture 8 provided with a bulb 9.

40 10 is a number plate which is secured to the panel 3, beneath the open lower end of the hood 6, and upon which are secured numbers 11. In order that the numbers 11 may be readily secured in position no matter how many figures are comprised in a num-

45 ber, I provide a series of parallel indicating lines 12, extending vertically across the number plate and placed an equal distance apart. At the upper end of the centre line are located indicating numbers 3 or 1 on the 50 lines at each side of the centre line, and at

the upper end of each side of the centre line are located the numbers 4, and also at the upper end of the outermost vertical lines, the number 2, also appearing adjacent to each of the lines at each side of the centre 55 line. At the upper end of each line intermediate between the two lines having the numeral 4 at the upper end thereof appears the numeral 3.

By this arrangement it will readily be 60 seen that anybody who is not used to setting up figures upon a number plate may easily set them up so that they be properly spaced apart no matter what number of figures is comprised in the number, and such number 65 placed centrally of the panel. If only one figure is used, such figure is placed and centred upon the centre line. If two figures are used they are centred upon the vertical lines at each side of the vertical line. If 70 three figures are used they are centred upon the centre line and in each line next to the outermost line, and if four figures are used they are centred upon the outermost lines 75 and the line at each side of the centre line.

The panel 3 may also carry a bell beneath the number plate. The lower end of the hood 6 necessarily must be open in order that the light may strike upon the number 11 so as to render it and the bell 13 clearly 80 visible to a caller at the house. In order to prevent moths or flies entering the hood and soiling the bulb, I preferably provide a removable screen 14, the inner edge of which is insertible within a groove 15 extending 85 transversely across the panel 3, its outer edge being secured by a suitable spring clip to the lower edge of the hood 6. The leading-in wires of the electric bulb may also extend through the mortar joint, as indicated 90 at 16.

From this description it will be seen that I have devised a very simple device which will have a very neat, attractive appearance, and which will clearly exhibit at all times 95 the house number and the house bell, in which the lamp bulb will be always kept clean and therefore emit a bright light, and from which such bulb may be easily removed when renewal is necessary, and at the 100

same time I have provided a number plate upon which numbers comprising various figures may be placed and properly centred by any unskilled person.

5 What I claim as my invention is:

A combination porch light and number plate comprising a supporting panel, an open bottomed hood secured to the panel and adapted to contain an electric light

bulb, and a number plate secured to the 10 panel beneath the open bottom of the hood provided with a plurality of vertical spacing lines having indicating figures located adjacent thereto corresponding to various numbers and figures to be attached to the 15 plate.

WILLIAM DOUGLAS.
